UNITED STATES PATENT OFFICE.

CLARENCE E. REED, OF WICHITA, KANSAS.

DEEP-WELL BORING AND CORING APPARATUS.

Application filed May 12, 1926, Serial No. 108,674. Renewed October 3, 1927.

The invention relates to core bits for deep well drilling, in which rotary toothed cutters are located at the bottom of the drill bit to cut the bottom of the hole and to leave a central core of the formation, which core is received by a core tube and when the apparatus is removed from the well, the core is gripped and retained in the core tube to be withdrawn with the apparatus from the well.

The invention consists in the features and combination and arrangement of parts hereinafter described and particularly pointed out in the claims.

15 In the drawings:

Figure 1 is a central vertical section of a bit head embodying the invention.

Fig. 2 is a bottom plan view of Fig. 1 with parts in section.

20 Fig. 3 is a vertical section in a plane a quarter turn from Fig. 1.

Fig. 4 is a vertical section of the center piece taken in the same plane as shown in Fig. 3.

25 In these drawings 1 is the bit head, having a core receiving tube 2 seated therein at 3 with an annular space 4 between it and the wall of the head for flushing fluid which finds access to the cutters through any suitable ports, an example of which is shown at 5.

The interior diameter of the core tube is preferably the same as that of the bore of the head at 6. Any suitable form of grip 35 or trap may be employed in the bore to engage the core of the formation and retain it in the core tube when the apparatus is withdrawn from the well, but as such device is common and does not enter into the novel 40 features of this invention, it is not shown herein.

The cutter mechanism for cutting the formation at the bottom of the well and for leaving a core standing at the axial center 45 of the well includes external toothed cutters 7 and 8 mounted to rotate on bushings 9, 10 which are screw threaded onto bosses 11, projecting laterally from the downwardly extending walls 13, 14 of the head. These 50 walls are at different distances from the axial center of the head, so that they will not track, that is to say, they will not describe the same circular path as the head is rotated about its vertical axis. The roller cutters 55 are disposed so that an annular path will be cut and provision made for compen-

sating for the wobble or oscillation of the bit head at the bottom of the hole. For this purpose, besides the external cutters above mentioned, other cutters are employed, 60 shown at 15, 16. These cutters are mounted to rotate on bosses 17, 18 of a center block 19, which has a bore 20 corresponding in diameter to the bore of the head. This block has its bosses arranged to bear in the walls 65 13 and 14, for which purpose the inner faces of these walls are provided with seat recesses 21 having shoulders 22 at their upper ends against which the ends of the bosses 17, 18 abut to sustain the thrust. This center 70 piece is of a shape, as shown in Fig. 2, to substantially fit the recess in the bottom of the drill head, and by bearing on the walls of said recess, said center piece is held 75 against turning.

This center piece is held in place by pins 23 which extend through openings in the bosses 11 of the head and into recesses or sockets 24 in the bosses 17, 18 of the center block. The bushings 9, 10 hold these pins in 80 place.

The center piece not only provides the bearings for the cutters 15, 16 and an extension of the bore for receiving the core left standing at the axial center of the apparatus, but it spaces the rotary cutters 15, 16 apart a greater distance than the diameter of the bore, and thus compensation is provided for the wobbling or oscillation of the bit, or its irregular movement in respect to 90 its axis at the bottom of the hole.

It is common practice in rotary wells of three thousand to four thousand feet depth and ten inches or eleven inches in diameter, to use a hollow pipe drill stem, of either five 95 inches or six inches in diameter, and experience has shown that in deep wells in so-called hard earth formation, the heretofore known core bits have sufficient lateral movement, due to the great depth and the flexibility of the drill stem, to wobble in the hole they make enough to reduce the diameter of the core, if any, left standing, so much that core lifting devices will not recover the core. In eleven inch cutting diameter bits, not infrequently the core is reduced three-fourths of an inch by bits whose inner cutting edges are spaced apart on a diameter of three to three and one-half inches.

100 With my improvement, as above set forth, there is provided a margin of safety in the

cutting action to prevent the core from being reduced beyond such diameter as will render the gripping means incapable of retaining the core within the core tube.

5. In addition to the cutters above described, the bit head is equipped with side roller cutters 25. These cut the clearance between the head and the side wall of the hole as well as the formation at the bottom of the 10 hole, their annular path being at a greater distance from the vertical center of the apparatus than the path of the cutters first mentioned. These side roller cutters can be journaled in place in any suitable manner.

15. In assembling the cutter organization, the cutters 15 and 16 are mounted on the bosses of the center piece and, as a unit, these parts are slipped into place, it being noted that the recesses 21 are open at their lower ends 20 so that the bosses 17, 18 can slip upwardly in these recesses until they abut against the shoulders 22. Then the pins 23 are inserted and the bushings are screwed into place, said bushings previously having had the roller 25 cutters 7, 8 mounted thereon.

I claim:—

1. In combination in a deep well boring and coring apparatus, a drill head having a bore to receive a core of the formation being cut, said head having walls extending down from its lower face, rotary cutters journaled outside said walls, a center piece between said walls having a bore forming a continuation of the bore of the head, and 35 having bearings on its outer sides, roller cutters on said bearings spaced thereby away from the edge of the bore and means for holding the said center piece in place.

2. In combination in a deep well boring 40 and coring apparatus, having a central bore to receive the core of formation left standing at the center of the bore of the hole, rotary cutters, a center piece having a bore corresponding to the bore of the head, said 45 center piece affording bearings for the cutters and spacing said cutters away from the

edge of the bore, and means for holding said center piece in place.

3. In combination in a deep well boring and coring apparatus, having a central bore 50 to receive the core of formation left standing at the bottom of the hole, said head having walls depending therefrom, a center piece between said walls having a bore corresponding to the bore in the head and having bosses on its outer side, rotary toothed 55 cutters mounted on said bosses and pins extending through the depending walls into said bosses to hold the same in place, substantially as described.

4. In combination in a deep well drilling apparatus, a bit head having a bore to receive a core of formation and having a recess in its lower face, a center piece arranged in said recess having a bore forming a continuation of the bore of the head, said center piece bearing on the walls of the recess to be held against turning thereby, roller cutters mounted on said center piece and between the same and the wall of the recess 70 and means for holding the center piece within the recess, substantially as described.

5. In combination with deep well drilling apparatus, a bit head having a bore to receive a core of formation and having a recess in its lower face, a center piece arranged in said recess having a bore forming a continuation of the bore of the head, said center piece bearing on the walls of the recess to be held against turning thereby, roller 75 cutters mounted on said center piece and between the same and the wall of the recess and means for holding the center piece within the recess, said means consisting of pins passing through the walls of the recess, 80 bosses on the exterior of said walls, bushings on said bosses holding the pins in position, and roller cutters mounted on said bushings, substantially as described.

In testimony whereof, I affix my signature.

CLARENCE E. REED.
